UNITED STATES PATENT OFFICE.

JAMES W. BRYCE, OF BINGHAMTON, NEW YORK, ASSIGNOR TO THE INTERNATIONAL TIME RECORDING COMPANY OF NEW YORK, A CORPORATION OF NEW YORK.

TIME RECORDER.

1,412,839.

Specification of Letters Patent. Patented Apr. 18, 1922.

Application filed November 27, 1920. Serial No. 426,714.

To all whom it may concern:

Be it known that I, JAMES W. BRYCE, a citizen of the United States of America, residing at Binghamton, in the county of 5 Broome and State of New York, have invented certain new and useful Improvements in Time Recorders, of which the following is a full, clear, and exact description.

10 In the use of workmen's time recorders and like devices, it is customary to install a master clock at some central point, and a plurality of secondary clocks at such points in the establishment as they may be needed 15 and by means of such secondary clocks, synchronized with the master clock, operate the time indicating mechanism of recorders. The workmen, coming, going, or starting and stopping work, insert their 20 cards in a recorder and by manually operating a handle print the time at appropriate points thereon.

Considerations of efficiency and practicability require that the secondary clocks 25 be capable of continuous operation, and for this reason they are habitually equipped with winding motors which at definite intervals are energized and caused to wind up the propelling weights or springs and here- 30 tofore the function of the motor has been solely to perform this operation, while that of the secondary clock is limited to setting the time indicating disks of the recorder from which the times on a card are printed 35 by the manual operation of the device.

It has been amply demonstrated that the more of manual operation that is left to the workman, the greater the probability of error arising from failure to properly perform 40 such operation, and much study and experiment have been expended in efforts to reduce and simplify the work which it is necessary for him to do in order to get the correct record on his card. This problem 45 I have sought to solve, but the main difficulty has been to accomplish it without adding to the complication of the apparatus, or increasing the number and expense of its essential parts, and this difficulty I have 50 succeeded in large measure in overcoming by the plan for which I now seek protection by Letters Patent.

According to my present invention I utilize the same motor both for winding the 55 secondary clock and for operating the time

recorder, that is, supplying the power necessary for performing the operations of printing, leaving to the workman only the responsibility of properly inserting his card and pushing a button which throws the recording mechanism into gear with the motor, which is thereby caused to work the printing mechanism. To do this in a way which will not interfere with its normal function of winding requires the use of 60 special devices which are hereinafter described. The drawings annexed illustrate the means employed for the purpose:

Fig. 1 is a view of a secondary clock and a recording machine equipped with the 70 means which I have devised for carrying out the invention.

Fig. 2 is an enlarged detail view of the magnet and associated means for connecting the motor to the winding mechanism. 75

Fig. 3 is a side view of the same.

Fig. 4 is a view in elevation of a drive shaft in the recorder with its associated parts.

Fig. 5 is a detail view of one of the cam 80 circuit controllers employed in the machine.

Fig. 6 is a detail view of a cam used in connection with a clutch on the shaft of Fig. 4.

Fig. 7 is a detail view of the means for 85 effecting the printing.

Fig. 8 is a wiring diagram showing the circuit connections of the clock and recorder which are directly involved in this improvement. 90

The clock as well as the recorder is or may be of any well known construction, and no further description of either, for purposes of this case, is required than to state that the clock, by means of a rod 1, operates the time indicating disks of the recorder, that at given times a workman inserts his card in the chute 2, and either by operating the handle 3, Fig. 7, manually, or by pressing a button hereinafter described, 95 operates the printing hammer or pad 4 to print the indicated time at the proper point on his card.

The clock contains a motor 5, which by means of an automatic circuit controller 6, 100 is thrown into operation periodically to wind the clock. Any means may be employed for this purpose, but in the present case I have shown a lever 7, which when shifted forces to the right a link 8 (see Fig. 110

8) which brings together two contacts 9, 10, and thereby closes the motor circuit to wind the clock by the rotation of a shaft 11. This is a standard form of winding mechanism in general use, and is described in detail in a patent granted to me on February 8, 1921, No. 1,367,534.

This shaft carries loosely mounted thereon a sleeve 12, having a worm 13 and said 10 sleeve has a toothed end, with which a similarly toothed sleeve 14, keyed to but slideable on the shaft, is adapted to be thrown into engagement by the armature lever 15 of an electromagnet 16, when said magnet 15 is energized. This magnet, as shown in Fig. 8, is in circuit with the motor 5, and when the motor circuit is closed through and by the contacts 9 and 10, the magnet is also energized and connects the worm with 20 the motor driven shaft 11 and thereby winds up the clock by means of a spur gear 66. It will be observed that the motor winds the clock only when the circuit of magnet 16 is closed.

25 The motor shaft carries at its end a bevel gear 17, which meshes with a similar gear 18 on a vertical revoluble rod 19, which by means of a gear 20 drives a short sleeve 22, on the drive shaft 21 of the recorder. This 30 sleeve has a toothed end and on the drive shaft 21 is a sleeve 23 with a similar toothed end which is normally impelled toward the sleeve 22 by a spiral spring 24. The sleeve is keyed to the shaft 21, but capable of sliding thereon.

35 Pivoted at 25 is a lever 26, normally drawn down by a spiral spring 27, and this lever when depressed operates as a stop to prevent the sleeve 23 from engaging with 40 the sleeve 22. The lever, however, constitutes the armature of an electromagnet 28 and when this magnet is energized it is raised to release the sleeve 23, and to thereby produce the rotation of the shaft 21.

45 On this shaft is a cam 29 upon which travels a stop 30, and when the shaft begins to turn the armature lever 26 is held up out of engagement with the sleeve 23, so that the circuit of magnet 28 may then be 50 broken without stopping the rotation of shaft 21, which does not stop turning until the stop 30 drops off the cam and permits the lever 26 to force back the sleeve 23 out of engagement with sleeve 22.

55 On the frame of the recorder is mounted a vertically movable plunger rod 31, with a push button 32 at its top end. On this rod are two pins 33, 34, and when the rod is pushed down the pin 33 forces to one side 60 a pivoted lever 35 which depresses the right-hand or free end of a contact lever 37. By the same movement the pin 34 depresses the left-hand arm of a lever 38, which thereby comes into engagement with contact lever 65 37, and by this means the motor circuit is

connected through wires 40, 41 and 42 to the electromagnet 28. The shaft 21 is now set in rotation.

On the shaft 21 is a pair of cams 43 and 51 with their contacts wired in multiple. 70 The purpose of these cams is to insure accurate timing of the making and breaking of the motor circuit and to maintain the current on the motor through a complete cycle of the recorder. In this case one revolution 75 of the shaft 21.

Immediately upon the starting of the shaft 21 the contacts on cam 43 fall off the rise of the cam and come together. As the revolution continues the contacts on cam 51 are 80 brought together. A little later, as the movement continues, the contacts on cam 43 are separated and the circuit is maintained closed by the contacts on cam 51 until at the close of the cycle they drop off the rise 85 of the cam 51 and the motor comes to rest, with clutch 23 disengaged.

Soon after shaft 21 starts rotating cam 47 moves catch 48 out of engagement with contact lever 37, permitting contact levers 37, 90 38 to separate. This would open the motor circuit were it not for the contacts on the cams 43 and 51.

The purpose of the construction of the starting button 32 etc. is to make it impossible to have the shaft 21 rotate more than once for one pressure of the starting button 32. With the construction shown, continued pressure on button 32 will cause the mechanism to function only once. 95

On the shaft 21 is a cam 49 that engages a roller on the printing lever 50, and by each revolution of the shaft 21 this lever is caused to throw the printing hammer 4, and print the card which is in the recorder. As previously explained, this lever may be worked by hand, if so desired. 105

It will be observed that at any time without reference to the conditions existing in the device, that is to say, whether the clock 110 is being wound or not, the depression of the key 32 will result in the operation of the printing mechanism but that such operation has no effect upon any other part of the clock mechanism.

From the above it will be seen that the winding and the printing operations as performed by the motor are independent of each other, and that the motor may be used for operating the recorder during the 120 periods in which it is winding the clock without in any way interfering with its operation. By means of this apparatus the duty imposed upon a workman in printing his time, is limited to the simple operation of 125 inserting the card and pushing a button, and this is a great practical advantage.

What I claim as my invention is—

1. The combination with a time recorder and a clock for controlling the time mecha- 130

nism of the said recorder, of a motor, means for periodically connecting said motor to the winding mechanism of the clock, and independently operated means for connecting 5 said motor to the printing mechanism of the recorder.

2. The combination with a time recorder and a clock for controlling the time mechanism of said recorder, of a motor, time controlled means for connecting the said motor to the winding mechanism of the clock, and manually controlled means for connecting 10 said motor with the printing mechanism of the recorder.

15 3. The combination with a time recorder and a clock for operating the time mechanism thereof, of a motor and a shaft driven thereby in the clock and a shaft for operating the printing mechanism in the recorder, 20 and electrically controlled means in both clock and recorder for connecting the motor shaft with the winding mechanism of the clock and connecting the said shaft with the printing shaft of the recorder.

25 4. The combination with a time recorder and a clock for operating the time mecha-

nism thereof, of a motor and a shaft driven thereby in the clock and a shaft for operating the printing mechanism in the recorder, 30 electrically controlled means in the clock for connecting the motor shaft with the winding mechanism, means in the recorder for connecting the printing shaft with the motor shaft, and means for interrupting such latter connection after one revolution 35 of the printing shaft.

5. The combination with a time recorder and a clock for operating the time mechanism thereof, of a motor and a shaft driven thereby in the clock, a shaft for operating 40 the printing mechanism in the recorder, clutches between said motor driven shaft and the winding mechanism of the clock, and the printing shaft of the recorder, and independently operating means for operating 45 said clutches whereby either the winding mechanism or the printing shaft may be connected with the motor driven shaft.

In testimony whereof I hereto affix my signature.

JAMES W. BRYCE.
